ABSTRACT OF THE DISCLOSURE

Aliphatic ω,ω di-(trifluoromethyl) perfluorocarboxylic acids and salts, esters and amides thereof. The acids have the structural formula:

wherein n is 2 to 21.

Methods for preparing such compounds by oxidizing compounds having the following structural formulae:

wherein

Y is Br or I;

X^1 and X^2 are each H, F, Cl, Br or I, but only one of X^1 and X^2 may be F;

X^3 and X^4 are each H, F, Cl, Br, I, OH, R, OR, OCR, OOCR, ROH, COOR, or COOH, R being an alkyl group having 1 to 3 carbon atoms;

X^5 and X^6 are each H, Cl, Br or I, but only one of X^5 and X^6 may be H;

m is an integer from 1 to 10; and

p is an integer from 2 to 3.

The acids and the derivatives have improved surface tension properties.

This invention relates to fluorine-containing compounds. More particularly, the invention pertains to the aliphatic

2

ω,ω -di-(trifluoromethyl)-perfluorocarboxylic acids having a group of the formula

attached to a terminal position. The invention further relates to the method of manufacturing said carboxylic acids.

The experience and research of the present inventors in the production of aliphatic perfluorocarboxylic acids and the properties thereof have shown that there are radical differences between the straight-chain perfluorocarboxylic acids and the branched-chain perfluorocarboxylic acids having a group of the formula

bonded to a terminal position, and that the latter excell much more compounds in utility than the former.

It is accordingly one object of this invention to provide a series of useful aliphatic ω,ω -di-(trifluoromethyl)-perfluorocarboxylic acids having as a side chain a trifluoromethyl group attached to a terminal position.

Another object of the invention is to provide aliphatic ω,ω -di-(trifluoromethyl)-perfluorocarboxylic acids displaying a marked ability in liquid media to decrease the surface tension of said media to a considerable extent.

A further object of the invention is to provide aliphatic ω,ω -di-(trifluoromethyl)-perfluorocarboxylic acids, the surface tension of which is no more than 18 dynes/cm. in the vicinity of the critical micelle concentration in aqueous media.

A still further object of the invention is to provide aliphatic ω,ω -di-(trifluoromethyl)-perfluorocarboxylic acids which can be profitably employed as raw materials for the manufacture of useful water and oil repellants and surface active agents.

A still further object of the invention is to provide aliphatic ω,ω -di-(fluoromethyl)-perfluorocarboxylic acids which can be employed as useful intermediates for the production of various types of fluorine-containing compounds.

A still another object of the invention is to provide a profitable process for the manufacture of aliphatic ω,ω -di-(trifluoromethyl)-perfluorocarboxylic acids having the aforesaid characteristics.

Other objects and specific features of the invention will become apparent in view of the following:

The aliphatic ω,ω -di-(trifluoromethyl)-perfluorocarboxylic acids of this invention are of the formula:

wherein n is an integer from 2 to 21.

The compounds of the aforesaid formula are:

Compound	B.P. in °C.	Compound	B.P. in °C.
CF_3	157	CF_3	189.
CF_3 $\text{CF}(\text{CF}_2)_2\text{COOH}$		CF_3

CF_3		CF_3	

The compounds of the aforesaid formula in which n is from 2 to 6 are liquids at normal room temperature, whereas the compounds of said formula in which n is from 7 to 21 are solids at normal room temperature. All of the compounds of said formula are acidic and excell in resistance to heat, chemicals and weather. Said compounds have a particularly pronounced low order of surface tension in that they exhibit no more than 18 dynes/cm. at the vicinity of critical micelle concentration in aqueous media.

Like the conventional straight-chain aliphatic perfluorocarboxylic acids, the branched-chain aliphatic ω,ω -di-(trifluoromethyl)-perfluorocarboxylic acids of this invention have a general tendency to decrease the surface tension of liquid media in which they are employed with an increase in the chain length of such branched-chain acids. As compared with the conventional straight-chain aliphatic perfluorocarboxylic acids, however, the branched-chain ω,ω -di-(trifluoromethyl)-perfluorocarboxylic acids of this invention having the same chain length or the same number of carbon atoms as the conventional compounds exhibit a markedly low order of surface tension. This outstanding feature of the invention is readily apparent from a review of the attached drawings. FIG. 1 is a graph on which the concentration in mole/liter of water of various compounds is plotted against the surface tension properties of the resulting solutions. FIG. 2 is a graph on which the concentration in mole/liter of water of various compounds is plotted against the surface tension properties of the resulting solutions.

In FIG. 1, lines A, B, and C represent such plottings for the compound

of this invention, and conventional compounds

and $\text{CF}_3(\text{CF}_2)_4\text{COOH}$, respectively. FIG. 2 is a graph on which similar plottings are made for compounds D, E and F, which are the compound

of this invention, and conventional compounds

and $\text{CF}_3(\text{CF}_2)_6\text{COOH}$, respectively.

As will be readily seen from the drawings, the compounds A and D of this invention always provide a lower order of surface tension, namely, a surface tension always below 18 dynes/cm. in concentrations both above and below the critical micelle concentration, than is provided by the conventional straight-chain compounds B and E which, respectively have the same chain length as com-

pounds A and D. Further, compounds A and D of this invention always provide a lower order of surface tension, particularly a markedly lower order of surface tension in a concentration below the critical micelle concentration, than the straight-chain compounds C and F, which respectively have the same number of carbon atoms as compounds A and D and a longer chain length than compounds A and D.

Such phenomena as specified above indicate the possibility that the branched-chain aliphatic ω,ω -di-(trifluoromethyl)-perfluorocarboxylic acids of this invention and the salts, esters, amides, nitriles and polymers derived therefrom, to excell much more in water and oil repellency and surface active properties than the corresponding straight-chain aliphatic perfluorocarboxylic acids and the derivatives thereof. In fact, the water and oil repellency experiments performed by the present inventors showed a marked difference in such properties between the two series of the compounds in question. For instance, an isopropanol solution containing 0.1 percent by weight of the chromium complex of a compound of the formula

of this invention imparts to gauze an ability to block the penetration of machine oil and liquid paraffin for more than 24 hours, whereas $\text{CF}_3(\text{CF}_2)_4\text{COOH}$ having the same number of carbon atoms but a longer chain could not protect gauze for no more than 10 minutes when employed under the same conditions as specified above, and $\text{CF}_3(\text{CF}_2)_3\text{COOH}$ having the same chain length could not even block the penetration of liquid paraffin when employed under the same conditions as specified before. Such excellent water and oil repellency can be secured by the aliphatic ω,ω -di-(trifluoromethyl)-perfluorocarboxylic acids of this invention when employed in the form of, not only chromium complexes, but as zirconium salts, aluminum salts, or polyesters obtained by esterifying polyvinyl alcohol, or rubber-like polymers prepared by polymerizing esters of any of the aliphatic perfluorocarboxylic acids of this invention and an unsaturated alcohol, such as allyl alcohol, or derived from unsaturated esters, such as of the formula

wherein n is as defined before, q is an integer from 2 to 4, and R' stands for a hydrogen or methyl group.

The aliphatic ω,ω -di-(trifluoromethyl)-perfluorocarboxylic acids of this invention and the derivatives thereof, further, possess marked surface active properties, exhibiting a pronounced ability for emulsifying, in aqueous media, polyfluorovinyl compounds, polyfluoroalkenes and the polymers thereof, so that the perfluorocarboxylic acids of this invention are very useful as agents for the emulsion polymerization of unsaturated polyfluoro compounds as disclosed herein. For instance, as described in Example 1 below,

of this invention provided a reaction speed and polymer concentration far greater than the straight-chain

having the same number of carbon atoms but a longer chain, when employed as an emulsifying agent for polymerizing tetrafluoroethylene in aqueous media under irradiation with ionizing radiations. As an emulsifying

agent for such reactions, the carboxylic acids and the water-soluble salts derived therefrom of the formula

M being sodium, potassium or ammonium, and n' being an integer from 2 to 21, particularly from 3 to 10, are profitably employed. The compounds of said formula not only have pronounced emulsifying ability but also excell in resistance to chemicals, heat and weather, so that the aqueous emulsions of the fluorine-containing polymers emulsified with said agent are useful compositions having a wide range of application. For instance, the anionic compounds of the formula

n being as defined before and r being an integer from 1 to 12, and the cationic compounds of the formula

are all profitably employed as useful surface active agents.

The aliphatic ω,ω -di-(trifluoromethyl)-perfluorocarboxylic acids of this invention can also be employed in the form of the original carboxylic acid or an acid anhydride as a profitable accelerator for the esterification reaction or the polymerization reaction of silicones. For instance, the derivatives of the formula

of this invention, n being as defined before, are particularly useful as a cockroach attractant.

Thus, the aliphatic ω,ω -di-(trifluoromethyl)-perfluorocarboxylic acids and the derivatives thereof of this invention are not only useful in themselves but as intermediates for preparing water and oil repellants, surface active agents, anti-fouling agents, dyestuffs, insect attractants, insecticides, heat-proof resins and rubbers, and similar articles.

The aliphatic ω,ω -di-(trifluoromethyl)-perfluorocarboxylic acids of this invention, further, possess lower melting points and higher solvent-solubilities than the straight-chain aliphatic perfluorocarboxylic acids having the corresponding number of carbon atoms, so that the compounds of this invention can be more easily processed than the conventional carboxylic acids. For instance,

of this invention is in a liquid state at normal room temperature, since the melting point thereof is about -10°C , whereas $\text{CF}_3(\text{CF}_2)_6\text{COOH}$ having the corresponding number of carbon atoms is in a solid state at normal room temperature, the melting point thereof being 55°C .

Not only the aliphatic ω,ω -di-(trifluoromethyl)-perfluorocarboxylic acids of this invention but the derivatives thereof possess a high order of solvent-solubility. For instance, a polyester having an ester value of 90 percent and which is obtained by esterifying in dimethyl formamide a polyvinyl alcohol having a polymerization degree

of 500 and a saponification value of about 100 percent with an acid chloride of

of this invention, can be easily dissolved in acetone or trifluorotrichloroethane, producing a homogeneous solution, whereas the polyester having an ester value of 90 percent and which is prepared under the same conditions as described before with $\text{CF}_3(\text{CF}_2)_5\text{COOH}$, which has the corresponding number of carbon atoms, is insoluble in acetone and difficult to dissolve in trifluorotrichloroethane, requiring a long period of stirring before being completely dissolved therein. These phenomena also verify the fact that the aliphatic ω,ω -di-(trifluoromethyl)-perfluorocarboxylic acids of this invention and the derivatives thereof can be easily employed and possess a wide range of application.

As stated before, the aliphatic ω,ω -di-(trifluoromethyl)-perfluorocarboxylic acids of this invention display a gradual decrease in surface tension properties with an increase in the chain length of the acid employed. This ability, however, almost flattens out when the value of n reaches 10 or more, and the synthesis of such compounds becomes increasingly difficult. The most desirable compounds of this invention, accordingly, are those compounds of the aforesaid formula having n in the range of from 3 to 10.

The aliphatic ω,ω -di-(trifluoromethyl)-perfluorocarboxylic acids of this invention are obtained by oxidizing any of the compounds of the following formulas:

wherein Y is $-\text{Br}$ or $-\text{I}$; X^1 and X^2 are respectively $-\text{H}$, $-\text{F}$, $-\text{Cl}$, $-\text{Br}$, or $-\text{I}$, said X^1 and X^2 being mutually exclusive in terms of $-\text{F}$; each of X^3 and X^4 is $-\text{H}$, $-\text{F}$, $-\text{Cl}$, $-\text{Br}$, $-\text{I}$, $-\text{OH}$, $-\text{R}$, $-\text{OR}$, $-\text{OCR}$, $-\text{OOCR}$, $-\text{ROH}$, $-\text{COOR}$, or $-\text{COOH}$, R being alkyl having from 1 to 3 carbon atoms; X^5 and X^6 respectively stand for $-\text{H}$, $-\text{Cl}$, $-\text{Br}$, or $-\text{I}$, said X^5 and X^6 being mutually exclusive in terms of $-\text{H}$; m is an integer from 1 to 10; and p is an integer from 2 to 3.

Representative compounds of Formulas I to IV are as follows,

being designated by R_f for brevity's sake.

(1) Compounds of Formula I:

(2) Compounds of Formula II:

(3) Compounds of Formula III:

(4) Compounds of Formula IV:

As an agent for oxidizing the compounds of Formulas I to IV, there are employed potassium dichromate and similar dichromates, potassium permanganate and similar permanganates, fuming sulfuric acid, or oxygen. Suitable oxidizing conditions should be determined in view of the species of the starting material and of the oxidizing agent to be employed. In the following are described the most desirable conditions for said oxidation reactions which are illustrative only and not limiting the scope and extent of the present invention.

(A) OXIDATION OF THE COMPOUNDS OF FORMULA I

The most desirable oxidizing agent for the oxidation of the compounds of Formula I is oxygen or fuming sulfuric acid.

(a) Oxidation with oxygen.—The starting material is oxidized with oxygen employed in the order of from 3 to 7 moles per mole of the starting material under the irradiation of light, particularly visible light, or ultraviolet rays. The initial reaction pressure ranges from normal atmospheric pressure to 20 kg./cm.², and the reaction temperature employed is from normal room temperature to about 50° C. There may be added chlorine, iodine or steam as an accelerator in the order of from $\frac{1}{10}$ of a mole to equimolar amounts. As a source of oxygen or oxygen-containing gases, such as air, are profitably employed.

(b) Oxidation with fuming sulfuric acid.—In this instance, there is employed a 10 to 70 percent fuming sulfuric acid in the order of from 2 to 6 times the original weight of the starting material in terms of SO_3 . The reaction is carried out at a temperature ranging from about 90° to about 170° C. under normal atmospheric pressure, or under increased pressure, where necessary.

(B) OXIDATION OF THE COMPOUNDS OF FORMULAS II TO IV

In addition to the aforesaid processes described under (A(a)) and (A(b)), there are employed as an oxidizing agent in the instant oxidation reactions permanganates or dichromates in amounts ranging from 1.5 to 5 moles per mole of the starting material in conjunction with an acid, such as concentrated sulfuric acid or glacial acetic acid, or an aqueous solution of alkali salt, such as sodium hydroxide or potassium hydroxide in the order of from an equimolar amount to 10 moles per mole of said oxidizing agent. The reaction is performed at a temperature ranging from normal room temperature to about 150° C. under a pressure of from normal atmospheric pressure to the vapor pressure of the compound to be oxidized at the reaction temperature.

(C) SYNTHESIS OF THE STARTING MATERIAL

The compounds of Formulas I to IV to be employed as the starting material in processes of this invention can be synthesized by various methods, but the most desirable process is to derive desired material from the compounds of the formula:

wherein Y and m are as defined before.

(1) Synthesis of the compounds of Formula I.—The compounds of Formula I are manufactured by the addition reaction of a compound of Formula V and a compound of the formula $CF_2=CX^1X^2$, X^1 and X^2 being as defined before, in the following manner:

(2) Synthesis of the compounds of Formula II.—The compounds of Formula II are produced by the addition reaction of a compound of Formula V and a compound of the formula $CH_2=CX^3X^4$, X^3 and X^4 being as defined before, in the following manner:

(3) Synthesis of the compounds of Formula III.—The compounds of Formula III are synthesized by the addition reaction of a compound of Formula V and acetylene or by dehydrohalogenation ($-HY$, Y being as defined before) of a compound of Formula II in the following manner:

(4) Synthesis of the compounds of Formula IV.—The compounds of Formula IV are manufactured by dehydrohalogenating ($-HX^6$ and $-HY$, X^6 and Y being as defined before) a compound of the formula

wherein Y, m and p are as defined before and which is obtained as a by-product accompanying the production of the compounds of Formula II which which is carried out by employing an unsaturated compound of the formula $CH_2=CX^3X^6$, X^5 and X^6 being as defined before.

Of the above reactions, the addition reactions of Equations VI, VII and VIII are carried out radically by the action of light, heat or a free radical initiator. An increase in the amount of the unsaturated compound employed generally promotes telomerization or similar

phenomena. In order to improve the yield of the addition product without producing any undesirable by-products, the amount of the unsaturated compound to be employed should be carefully determined in view of the properties of the compound of Formula V to be employed therewith. Said amount also varies with the degree of self-polymerization potential. For instance, a compound having a high order of self-polymerization potential, such as

$CH_2=CHCOOCH_3$ or $CH=CH$, is preferably employed in the order of from 0.1 to 0.9 mole per mole of the compound of Formula V. In order to raise conversion levels, such unsaturated compounds are added not in a single charge but incrementally or continuously. An unsaturated compound having a low order of self-polymerization potential, such as $CHCl=CHCl$, $CF_2=CCl_2$ or $CF_2=CHF$ is employed in an equimolar amount or may be added in excess in relation to the compound of Formula V.

- 20 When light is employed at the initial stage of reaction, visible light or ultraviolet rays is preferably employed at a temperature ranging from normal room temperature to about 100° C. The reaction pressure varies with the vapor pressure of the stock material. For instance, $CH_2=CHCl$, $CH_2=CH_2$, $CH=CH$ or $CF_2=CHF$ is preferably allowed to react in a closed vessel under autogenous pressure. There may however be employed an increased pressure ranging from 1 to 50 kg./cm.². A reactant having a higher order of boiling point is employed in an open vessel by cooling under a reflux condenser. When heat is employed to initiate the reaction, the reaction is preferably carried out in a closed vessel at a temperature ranging from 150° to 250° C. or thereabout. When a free radical initiator is employed, the reaction is desirably carried out at a temperature ranging from normal room temperature to about 150° C. under a pressure from 1 to 50 kg./cm.². The free radical initiator employed in processes of this invention tertiarybutylhydroperoxide, tertiarybutylperoxide, benzoylperoxide, diisopropylperoxydicarbonate and similar organic peroxides, or azobisisobutyronitrile and similar organic azo compounds.

45 The dehydrohalogenating reaction of Equations IX and X can be carried out in various ways. Particularly, said reaction is desirably performed with an alkali metallic compound, such as potassium hydroxide, sodium hydroxide or sodium carbonate, or with an alkali metal, such as metallic sodium, in a saturated alcohol, such as methanol, ethanol or isopropyl alcohol, in an open or a closed vessel at a temperature ranging from normal room temperature to about 100° C. Said dehydrohalogenating reaction, however, requires no particular reaction conditions. Any conventional method may be profitably employed.

The compounds of Formula V, namely, of the formula

60 m and Y being as defined before, and which are employed as a starting material for the production of the compounds of Formulas I to IV are synthesized by the reaction of a perfluoroisopropyl halide of the formula

70 Y being as defined before with tetrafluoroethylene by various procedures. It is desirable, however, to carry out the reaction with the aid of irradiation by ionizing radiation, a method which was devised by the present inventors and disclosed in their Japanese patent application No.

6,569/1964. Alternatively, the reaction may be profitably carried out in the presence of a free radical initiator, a method which was also devised by the present inventors and disclosed in our Japanese patent application No. 6,570/1964.

The irradiation sources employed in the former method include α -rays, β -rays, γ -rays, X-rays, neutron rays, proton rays, deuteron rays and similar ionizing radiations, of which γ -rays, particularly γ -rays emitting from Co^{60} are most preferable. The dosage rate ranges from 1×10^2 r./hr. to 1×10^6 r./hr., particularly from 1×10^3 r./hr. to 1×10^5 r./hr., preferably within the total dosage range of from 1×10^3 to 1×10^6 r. The reaction temperature and reaction pressure can be varied over a wide range. Namely, the reaction temperature to be used ranges from about the temperature of the liquid nitrogen employed to about 150° C., particularly from -90° to 100° C. Either reduced or elevated pressure may be used, but the reaction satisfactorily proceeds under normal atmospheric pressure or a pressure amounting to about 50 kg./cm.². The starting perfluoroisopropyl halide is preferably employed in the order of from 1 to 10 moles for 10 to 1 moles of the tetrafluoroethylene to be employed therewith.

The free radical initiator employed in the latter of the aforesaid methods includes benzoylperoxide, ditertiarybutylperoxide, tertiarybutylperbenzoate, tertiarybutylhydroperoxide and similar organic peroxides, and azobisisobutyronitrile and similar organic azo compounds. The amount of said initiator to be employed ranges from 0.05 to 10 percent by weight, particularly from 0.5 to 5 percent by weight, in relation to the stock material. The reaction conditions vary with the properties of the initiator to be employed, but the reaction is profitably carried out at a temperature ranging from 50° to 200° C. under a pressure of from 5 to 200 kg./cm.². In this reaction, the starting perfluoroisopropyl halide is employed in amounts of the order of from 1 to 5 moles for 5 to 1 mole of tetrafluoroethylene, preferably from 1 to 3 moles per mole of tetrafluoroethylene. Whether ionizing radiations or free radical initiators are employed, the reaction can be satisfactorily carried out batchwise or discontinuously or continuously.

Thus, the desired aliphatic ω,ω -di-(trifluoromethyl)-perfluorocarboxylic acids of this invention can be easily obtained as noted above from intermediates prepared by the reaction of the readily available perfluoroisopropyl halides with tetrafluoroethylene, thus producing the compounds of Formula V, from which the compounds of Formulas I to IV can be prepared.

In the following are described the preferred methods employed in this invention for the production of the compounds of the formula

m being as defined before:

(1) There were placed in a 500-cc. Hastelloy-C agitator-type autoclave, Hastelloy being a trade name, Union Carbide Corp., U.S.A., 185 grams (0.625 mole) of perfluoroisopropyl iodide of the formula

0.7 gram of tertiarybutylhydroperoxide, and 3.3 grams of ditertiarybutylperoxide. After freezing the mixture with liquid air, the air present in the autoclave was evacuated under reduced pressure. There were then added 35 grams of tetrafluoroethylene, and the mixture was agitated while passing steam therethrough. The reaction temperature rose to 100.5° C. and the maximum pressure reached 20.5 kg./cm.² 10 minutes after application of the steam heating, but the pressure started gradually falling thereafter. When the pressure fell to 6 kg./cm.² 5 hours after appli-

cation of the steam heating, agitation and steam heating were suspended and the autoclave was cooled with water. Then the pressure fell to almost 0 kg./cm.², producing 217 grams of reaction products. When the reaction products were fractionally distilled, there were obtained:

For a fuller understanding of the principles of this invention, there are provided in the following the preferred examples which are illustrative only and not limiting in any sense of the scope and extent of the invention.

EXAMPLE 1

Synthesis of CC(F(C(F)C(F)C(F)I)C(F)C(F)I)I

In a 150-cc. Hastelloy-C autoclave there were placed 150 grams (0.303 mole) of

7 grams (0.250 mole) of ethylene, and 1 gram of azobisisobutyronitrile. The air present in the autoclave was then evacuated, and the mixture was agitated at 60° to 70° C. for 5 hours. After separating 2.5 grams of unreacted ethylene, the liquid reaction mixture in the autoclave was fractionally distilled, producing 69.3 grams of an addition product of the formula

5.9 grams of other fractions, and 79.3 grams of unreacted

In a 100-cc. four-neck flask, in the next step, there were placed with stirring 18 grams of potassium hydroxide and 20 grams of ethanol. After complete agitation, there were added portionwise 68 grams of the aforesaid crude

while maintaining the reaction temperature at around 50° to 60° C. by cooling the rising temperature due to the exothermic reaction. After such addition was completed, the temperature was raised to 80° C. and the agitation was continued for an additional 1 hour.

The resulting reaction product was then poured into 200 cc. of water. After separation of the oil phase, the liquid phase was extracted with chloroform. The resultant extract and the oil phase were then dehydrated together with magnesium sulfate anhydride and fractionally distilled after removing the chloroform, producing 49.5 grams (0.121 mole) of

Yield was 96.2 percent on a mole basis.

48 grams (0.121 mole) of the product thus obtained were then stirred at 120° to 135° C. for 8 hours with a mixture of 74 grams of potassium dichromate, 162 grams of concentrated sulfuric acid and 58 grams of distilled water, and steam-distilled. The extract was then neutralized with a 5 percent potassium hydroxide aqueous solution, evaporated and dried. The solid residue thus separated was placed in excess concentrated sulfuric acid and distilled under reduced pressure, producing 48 grams of

of B.P. 85° to 88° C./6 to 8 mm. Hg.

Analysis.—Calcd. (percent): C, 23.2; F, 68.8; H, 0.24. Found (percent): C, 23.0; F, 69.1; H, 0.27.

Other properties: M.P. -10.5° to -11.0° C.; n_D^{25} , 1.3134; d_4^{25} , 1.76 g./cc.

The compound thus prepared was neutralized with sodium hydroxide and recrystallized with toluene-n-butanol anhydride, producing dried

which displayed a marked effect on the emulsification polymerization of tetrafluoroethylene in aqueous media.

Namely, there were placed in a 2-liter agitator-type autoclave 0.3 percent by weight of said

and 6 percent by weight of n-cetane as a stabilizer in 800 cc. of deoxidized distilled water. After evacuating the air present in the autoclave, tetrafluoroethylene gas was introduced to pressurize the autoclave to the level of about 6 kg./cm.² and the mixture was completely agitated. The mixture was then subjected to irradiation of γ -rays emitting from a 2,000-curie Co⁶⁰ source. As the polymerization reaction progressed polymerization, the reaction temperature gradually fell. To compensate for this drop in the temperature, additional tetrafluoroethylene was supplied to keep the reaction pressure at the level of about 6 kg./cm.². After sustaining an irradiation dosage of 8×10^4 r., the mixture was allowed to post-polymerize for as additional 30 minutes. The resultant dispersion had a polymer concentration of 28.7 percent by weight, and the maximum reaction velocity was 4.1 moles per liter per hour, whereas when CF3(CF2)6COONa was employed as an emulsifying agent as a control under the same conditions there was produced a dispersion having a polymer concentration of 20 percent by weight with the maximum reaction velocity reaching no more than 3.0 moles per liter per hour.

EXAMPLE 2

Synthesis of CC(F(C(F)C(F)C(F)I)C(F)C(F)I)I

In a 500-cc. autoclave there were placed 155 grams (0.392 mole) of

and 1.7 grams of azobisisobutyronitrile, and the mixture was frozen with liquid air. After evacuating the air present in the autoclave, there were introduced 9.1 grams (0.350 mole) of purified acetylene, and the mixture was agitated at 90° to 100° C. for 7 hours while heating by steam. There were then separated 2.1 grams of unre-

15

acted acetylene, and the reaction mixture was fractionally distilled, producing 92.5 grams (0.219 mole) of

67.7 grams of unreacted

and 1.6 grams of other substances.

92 grams of the product.

thus produced were then oxidized with a mixture of 175 grams of potassium dichromate, 378 grams of concentrated sulfuric acid, and 137 grams of distilled water, and treated as described in Example 1. The resultant products contained 58.1 grams (0.185 mole) of

of B.P. 62° to 68° C./14 to 16 mm. Hg. Yield was 47.2 mole percent. Other properties were: M.P., -21.6° C.; n_{D}^{25} , 1.3160; d_4^{25} , 1.65 g./cc.

EXAMPLE 3

In a 150-cc. Hasteloy-C autoclave there were placed 150 grams (0.252 mole) of

12.5 grams (0.200 mole) of vinyl chloride, and 1.9 grams of azobisisobutyronitrile, and the mixture was frozen with liquid air. After evacuating the air in the autoclave, the mixture was agitated at 100° to 110° C. for 90 minutes while heating with superheated steam. The reaction pressure fell from an initial value of 7.8 kg./cm.² to 2 kg./cm.². When further cooled to about room temperature, the pressure in the autoclave fell to an order level lower than normal atmospheric pressure, and no unreacted vinyl chloride separated out. When the resultant liquid reaction mixture of 162.1 grams was fractionally distilled, there were obtained 38.1 grams (0.064 mole) of unreacted

118.5 grams (0.180 mole) of

and 5.4 grams of other substances. Yield was 95.8 percent by mole.

Conversion:

74.6 percent on a mole basis.

Vinyl chloride: 100 percent on a mole basis.

16

In the next step, there were placed in a 300-cc. four-neck flask 118.2 grams of the resultant

144 grams of potassium dichromate, and 113 grams of distilled water. There were then added portionwise with stirring 3.12 grams of concentrated sulfuric acid for 2 hours. Such a very active exothermic reaction took place, that the exothermic heat was controlled at the initial stage. After the completion of such addition, agitation was continued for an additional 3 hours at a refluxing temperature. When the reaction was completed, the mixture was steam-distilled, neutralized with diluted sodium hydroxide, evaporated to remove the water, extracted with ethanol to remove the sodium iodide, and filtered. The ethanol being removed, the filtrates were distilled with concentrated sulfuric acid employed in an amount of about 2.5 times the original weight of the filtrates, producing 81.1 grams of

of B.P. 74° to 76° C./1.5 to 2.5 mm. Hg.

Analysis.—Calcd. (percent): C, 23.34; F, 70.23; H, 0.19. Found (percent): C, 23.51; F, 69.88; H, 0.21.

Infrared absorption showed ν c=0 at 5.67. Yield was 88.2 percent on a mole basis.

EXAMPLE 4

In a 500-cc. stainless steel autoclave there were placed 248 grams (0.5 mole) of

and 3.4 grams of tertiarybutylperoxide, and the mixture was frozen with brine cooled with Dry Ice. After evacuating the air in the autoclave with nitrogen gas and then with $\text{CF}_2=\text{CFCl}$ gas, there were added 46.6 grams (0.400 mole) of $\text{CF}_2=\text{CFCl}$, and the mixture was agitated carefully at 120° to 130° C. A violent reaction took place during the initial 30 minutes after the application of agitation, but the reaction gradually slowed down. When the reaction pressure fell to a constant level of 2.2 kg./cm.² 3.5 hours after the application of agitation, the reaction mixture was cooled to normal room temperature with cold water. There were thus obtained 295 grams of a liquid product containing almost no unreacted $\text{CF}_2=\text{CFCl}$. The product thus obtained was then placed in a two-neck flask and fractionally distilled while passing nitrogen gas through the capillary tubes, producing 126.8 grams (0.256 mole) of unreacted

of B.P. 75° to 76° C./4.0 mm. Hg, 90.6 grams (0.148 mole) of

48.1 grams (0.066 mole) of

and 26.9 grams of other substances, totaling 156.6 grams in all. Conversion of

was 48.8 percent on a mole basis, and yield of

was 60.7 percent on a mole basis.

90 grams (0.147 mole) of the resultant

were then oxidized with fuming sulfuric acid at 150° C. for 10 hours, and the resultant

was hydrolyzed, producing

of B.P. 75° to 76° C./3.5 to 4.0 mm. Hg. Infrared analysis indicated ν_c at 5.66.

EXAMPLE 5

210 grams (0.302 mole) of

were reacted with 14 grams (0.250 mole) of $\text{CH}_2=\text{CHCH}_2\text{CH}_3$ and 2.5 grams of ditertiarybutylperoxide at 120° to 130° C. for 4 hours. After separating 2.0 grams (0.036 mole) of unreacted $\text{CH}_2=\text{CHCH}_2\text{CH}_3$ and 66.8 grams (0.096 mole) of unreacted

there were obtained 0.194 mole of a 1:1 molar addition product and 9.2 grams of other substances. Conversion of

and $\text{CH}_2=\text{CHCH}_2\text{CH}_3$ were respectively 68.2 percent on a mole basis and 85.6 percent on a mole basis. Yield of the 1:1 molar addition product was 94.2 percent on a mole basis.

With the resultant 1:1 molar addition product there were then reacted with stirring 260 grams of sodium permanganate and 1,500 grams of glacial acetic acid at 100° C. for 10 hours. After decoloring the resulting product with sulfuric acid gas, the acetic acid was removed by distillation, and the separated solids were placed in 10 percent H_2SO_4 and continuously extracted with ether. To the resultant ether solution there was added methanol in a quantity of about 2 times the original volume of ether, and the mixture was carefully neutralized with a 20 percent sodium hydroxide aqueous solution, evaporated, and dried, producing 108 grams of light brownish solids. When fractionally distilled with 75

concentrated sulfuric acid, there were obtained 98.2 grams of

of B.P. 70° to 75° C./1.0 to 1.5 mm. Hg.

Analysis.—Calcd. (percent): C, 23.45; F, 71.18; H, 0.16. Found (percent): C, 23.89; F, 70.09; H, 0.14.

Molecular weight.—Calcd.: 614.18. Found: 612.5.

Yield: 82.5 percent on a mole basis.

EXAMPLE 6

In a 500-cc. 4-neck flask in which the air was completely replaced with nitrogen gas there were placed 20 396 grams (1.00 mole) of

25 86 grams (1.00 mole) of purified vinyl acetate, and 1.2 grams of azobisisobutyronitrile, and the system was heated at 60° to 75° C. for 6 hours. There were then further added 39.6 grams of

35 and 1.2 grams of azobisisobutyronitrile, and the mixture was heated at 75° to 85° C. for 3 hours. When unreacted

40 and vinyl acetate were separated, there were obtained 419 grams of crude $\text{C}_9\text{F}_{11}\text{H}_6\text{O}_2\text{I}$.

Analysis.—Calcd. (percent): C, 22.4; F, 43.3; I, 26.4; H, 0.21. Found (percent): C, 23.0; F, 42.1; I, 26.9; H, 0.26.

45 400 grams of the crude product thus obtained were reacted with 93 grams of potassium hydroxide in 100 cc. of ethanol, and the mixture was poured into 600 cc. of water, extracted with chloroform, dried with magnesium sulfate anhydride, and heated to expel the chloroform. The brownish liquid residue of 297 grams thus obtained was placed in a 2-liter 4-neck flask and oxidized with stirring with 700 grams of potassium dichromate and 1,700 grams of concentrated sulfuric acid in 567 grams 50 of distilled water at 120° to 135° C. for 8 hours. The resultant mixture was then steam-distilled, neutralized with 5 percent potassium hydroxide, and heated to dispel the water, producing 273 grams of light yellowish powder. When fractionally distilled with concentrated sulfuric acid under reduced pressure, there were obtained 99.0 55 grams of

60 of B.P. 55° to 58° C./10 to 11 mm. Hg.

Molecular weight.—Calcd.: 314.06. Found: 312.1.

Infrared absorption: $\nu_c=0$ at 5.68.

EXAMPLE 7

19

In a 150-cc. pressure glass cylinder were placed 89.8 grams (0.20 mole) of

of B.P. 51° to 52° C./60 mm. Hg and 9.7 grams (0.10 mole) of cis-1,2-dichloroethylene, and the mixture was frozen with liquid air. After closing the cylinder airtight, the air present was evacuated, and the temperature was gradually raised with stirring to allow the two ingredients to mix thoroughly. When the temperature was raised to about room temperature, the cylinder was placed 10 cm. apart from a 2,000-curie Co^{60} source and subjected for 3.5 hours to irradiation of γ -rays emitting from said source. Fractional distillation of the irradiated sample produced a 1:1 molar addition product (yield: 21.5 percent on a mole basis) and 1:2 molar addition product (yield: 10.3 percent on a mole basis).

Analysis.—Calcd. for $\text{C}_9\text{F}_{15}\text{Cl}_2\text{BrH}_2$ (percent): C, 20.8; F, 52.2; Cl, 13.0; Br, 14.6. Found (percent): C, 20.2; F, 51.3; Cl, 13.1; Br, 14.1.

Analysis.—Calcd. for $\text{C}_{11}\text{F}_{15}\text{Cl}_4\text{BrH}_4$ (percent): C, 20.5; F, 44.3; Cl, 22.1; Br, 12.4. Found (percent): C, 20.4; F, 43.1; Cl, 23.8; Br, 11.7.

When 15 grams of said

were oxidized with potassium chromate, concentrated sulfuric acid and distilled water as described in Example 1, there was obtained the desired

in a yield of 84.7 percent on a mole basis.

EXAMPLE 8

In a 500-cc. stainless steel autoclave were placed 198 grams (0.500 mole) of

3.4 grams of tertiarybutylperoxide, and the mixture was frozen with brine cooled with Dry Ice. After replacing the air in the autoclave with nitrogen gas, there were added 46.6 grams (0.400 mole) of CF_2CFCl . The mixture was then carefully warmed and stirred at 120° to 130° C. A violent reaction took place for the initial 30 minutes after the application of stirring. But the reaction gradually slowed down thereafter, and the pressure fell to the constant level of 2.2 kg./cm.² 3.5 hours after the application of stirring. When the resultant mixture was allowed to cool to normal room temperature, there were obtained 245 grams of a liquid reaction mixture containing almost no unreacted CF_2CFCl . Fractional distillation of the mixture produced 81.2 grams (0.205 mole) of

130 grams (0.254 mole) of

20

of B.P. 57° to 58° C./2 to 3 mm. Hg, and 31.9 grams of other substances.

There were then placed in a 150-cc. autoclave equipped with a window 51.3 grams (0.100 mole) of said 1:1 molar addition product, 10.1 grams of chlorine gas, and 15.5 grams of oxygen, and the mixture was subjected to irradiation; at normal room temperature for 35 hours, by ultraviolet rays applied through the window. After collecting in a collector cooled with liquid air the volatile gases including the chlorine, the liquid residue was fractionally distilled, producing 26.1 grams of

of B.P. 68° to 70° C. in a yield of 71.3 percent on a mole basis and having an intense $\nu_{\text{C}}=0$ infrared absorption at 5.27, 10.5 grams (0.0205 mole) of unreacted

and 2.1 grams of other substances. Conventional hydrolysis of 10 grams of said reaction product produced

of B.P. 67° to 70° C./10 mm. Hg in a yield of 93.8 percent on a mole basis.

While the invention has been described with particular reference to specific embodiments, it is to be understood that it is not to be limited thereto but is to be construed rather broadly within the scope and extent of the appended claims.

We claim:

1. A method of preparing an ω,ω' -di-(trifluoromethyl)-perfluorocarboxylic acid of the formula:

wherein n is an even integer from 2 to 20, which comprises oxidizing with at least one member of the group consisting of alkali metal chromate, alkali metal permanganate, fuming sulfuric acid and oxygen, a compound selected from the group consisting of the compounds of the formula:

wherein Y is a member selected from the group consisting of —Br and —I; X^3 and X^4 are each a member selected from the group consisting of —H, —F, —Cl, —Br, —I, —OH, —R, —OR, —OCR, —OOCR, —ROH, —COOR and —COOH, R being alkyl having from 1 to 3 carbon atoms; and m is an integer from 1 to 10.

2. A method of preparing an ω,ω' -di-(trifluoromethyl)-perfluorocarboxylic acid of the formula:

wherein n is an even integer from 2 to 20, which comprises oxidizing with fuming sulfuric acid at a tempera-

21

ture of from 90 to 170° C., a compound selected from the group consisting of the compounds of the formulas:

wherein Y is a member selected from the group consisting of —Br and —I; X³ and X⁴ are each a member selected from the group consisting of —H, —F, —Cl, —Br, —I, —OH, —R, —OR, —OCR, —OOCR, —ROH, —COOR and —COOH, R being alkyl having from 1 to 3 carbon atoms; each of X⁵ and X⁶ stands for a member selected from the group consisting of —H, —Cl, —Br, and —I; said X⁵ and X⁶ being mutually exclusive in terms of —H; m is an integer from 1 to 10; and p is an integer from 2 to 3.

3. A method according to claim 2 wherein said compound has the formula:

22

4. A method according to claim 2 wherein said compound has the formula:
